CLAIM

The ornamental design for a ratchet drive control bar, or similar article, as shown and described.

DESCRIPTION

FIG. 1 is a top plan view of the ratchet drive control bar or similar article showing my new design with a ratchet wrench being shown in broken lines for illustrative purposes only;

FIG. 2 is an enlarged side elevational view thereof with the head of a drive wrench being shown in broken lines for illustrative purposes only;

FIG. 3 is an enlarged perspective view thereof;

FIG. 4 is an enlarged end elevational view thereof;

FIG. 5 is an enlarged opposite end elevational view thereof.
